CHARLES E. BENNETT AND CHARLES G. ADSIT, OF ATLANTA, GEORGIA, ASSIGNEES, BY
MESNE ASSIGNMENTS, TO BALT MANUFACTURING COMPANY, OF ATLANTA, GEORGIA,
A CORPORATION OF GEORGIA.

ELECTRIC SWITCH.

Application filed September 9, 1919, Serial No. 322,642. Renewed September 12, 1924.

To all whom it may concern:

Be it known that we, CHARLES E. BENNETT and CHARLES G. ADSIT, citizens of the United States, residing at Atlanta, in the county of Fulton and State of Georgia, have invented certain new and useful Improvements in Electric Switches, of which the following is a specification.

Our invention relates to electric switches, and particularly to heavy duty switches for installation in power lines of medium or high voltage for either direct or alternating current. The object of our invention is to provide a switch of high capacity having means for automatically cooling and quenching the arc which tends to form on the opening of the switch, an energy absorbing medium too cold for the arc to be maintained.

20 In the accompanying more or less diagrammatic drawings—

Fig. 1 is a vertical section through a switch in which my invention is embodied in one form, and showing the switch in closed position;

Fig. 2 is a similar view showing the switch open;

Figs. 3 and 4 are similar views of a modified construction; and

30 Figs. 5 and 6 are similar views of a second modification.

As shown in the more or less diagrammatic embodiment of our invention illustrated, the switch comprises, in the form indicated in Figs. 1 and 2, a tank or other liquid container 6 for an electrolyte 9, of rapid and high heat absorbing capacity, such as water, which partially fills the tank.

A tube 5, preferably of insulating material, 40 dips at its lower open end into the electrolyte, but is closed at its upper end by a plug 12 pierced by a vent 4 and by a central hole through which slides the conductor rod 3 which forms the movable member of the 45 switch proper. An air space 10 is confined between the electrolyte in the tube and the plug 12 of the upper end thereof. At the lower end of the rod 3 is the terminal 11, here shown in the form of a conical plug 50 adapted to enter the cooperating terminal cup 7 mounted on the bottom of the tank and submerged in the electrolyte 9. Any suitable means may be employed to operate the rod 3. As here shown it is connected at

its upper end to a link *a* depending from 55 one arm of the balance lever *b* to which the pull rod *c* is connected. The balance lever *b* is pivoted to a standard *d*, which may be supported in any suitable way, as for instance upon the tank 6, an insulator 16 being interposed between the standard *d* and the tank. Current is led to the switch through the main 1, the portion 2 of which is clamped, or in any other way secured, to one branch of the balance lever *b*. The 60 outgoing main 8 is attached to the tank or otherwise brought into electrical connection with the terminal 7 within the tank.

When the rod 3 is lifted the terminal 11 parts from terminal 7 and an arc tends to 70 form therebetween. As the rod moves rapidly upward the arc passes through the electrolyte now separating the terminals. This liquid performs the very important function of absorbing or cooling the heat 75 energy of the arc, and thus tends to rapidly quench it. Should the arc not be quenched instantly the heat generated by it causes the electrolyte in the tube, and also the air or vapor in the air space 10, to expand, thus 80 expelling the liquid from the lower end of the tube. The arc is thus not only in direct contact with the liquid, which absorbs the heat thereof, but the circulation of the liquid caused by its expulsion from the tube 85 5 through the path of the arc, breaks the arc and opens the circuit. The vent 4 is provided to prevent excessive pressure in the tube 5, which forms an expansion chamber within the tank, the arc being drawn in 90 this expansion chamber and through the liquid therein.

In Figs. 3 and 4 we have shown a modified arrangement by which a double break in series is secured. This is attained by making the tank 6 of sufficient size to accommodate two insulating tubes 5, through the head of each of which passes a conducting rod 3 connected at its upper end to an insulating bridge piece *e*. The mains 1 and 8 are 95 connected respectively to the two rods 3, and in the closed position of the switch the circuit is completed between the fixed terminals 7 either through the electrolyte or through the tank, or both. The rods are lifted by 100 the balance lever *b* connected to the insulation bridge piece *e* through the insulator 16, mounted in the link *a*. In this form we have 105

also shown the tank 6 insulated by mounting it on insulators 15 in a surrounding tank 14, from which it is separated by a quantity of oil 13, or other insulating material. The outer tank may for additional protection be grounded at *g*. On the opening of the switch the arcs which tend to form between the switch terminals 11 and the fixed terminals 7 are quenched in precisely the same manner as that above described.

In Figs. 5 and 6 we have shown an arrangement in which the position of the parts is reversed, the fixed terminals 7 being arranged in the upper portion of the expansion chamber, and the movable terminals 11 adapted to be drawn down into the liquid in the lower portions of the tubes 5 when the switch is opened. The operation is substantially the same as that above described, since the heat of the arc not only exposes the air or vapor in the chamber 10, but also vaporizes the liquid with which it comes in contact and the arc is quenched. It is of course possible to so lengthen the tank 6 that the rods 3 are drawn down a sufficient distance to carry the movable terminals 11 below the lower end of the insulating tubes, but we have found such a construction unnecessary to the efficient operation of the switch.

The present switch is particularly effective in interrupting tenacious arcs produced between the switch terminals in a high voltage direct or alternating current circuit. The heat of the arc is absorbed by a medium which tends to cool and quench the arc. The function of the expansion chamber is important since the expulsion of the electrolyte from the tube causes rapid circulation of the electrolyte in the apparatus and forces the water or other liquid into direct contact with the arc, thereby absorbing the heat of the latter. It is impossible to maintain an arc between two points of contact submerged in the liquid when the latter is rapidly circulated. An arc produced through a body of water or the like, when it is in static condition, forms a hole in the water, the diameter of the hole, so to speak, varying with the amount of energy passing through the arc above. Upon the slightest agitation of the liquid, however, this hole is broken up and the path of the arc is lengthened and cooled at the same time, and the arc immediately quenched. This phenomenon is utilized in the present apparatus to quench the arc in a most efficacious manner.

Of course the normal liquid level in the tube and tank is reestablished at once upon the quenching of the arc, since the vent 4 permits the escape of the air and the steam generated in the expansion chamber and permits the liquid to rise again to its predetermined level.

The operation of this switch is obviously unlike in principle to that of an oil switch,

in which the interruption of the arc is dependent upon the insulating qualities of the liquid (oil) surrounding the contacts. On the contrary, the liquid of the present interrupter is a conductor, and the quenching of the arc is dependent solely upon its attenuation in a medium which rapidly absorbs the heat of the arc, and at the same time breaks up its normal path.

Furthermore, when an electric arc is formed between two contacts, partial volatilization of the contacts themselves occurs, forming a conductive gas which tends to provide a path of low resistance between the contacts and thus to facilitate the maintenance of the arc. This cannot occur, however, when the contacts are immersed in a liquid that has high heat absorbing qualities and that is vaporized and rapidly circulated as a result of the formation of the arc in contact therewith.

The particular construction and arrangement of parts illustrated may obviously be variously modified without departing from what we claim as our invention.

We claim—

1. An electric switch comprising a liquid container, a readily vaporizing electrolyte of high heat absorbing capacity contained therein, a member at least partially submerged in said electrolyte and having an interior chamber open to said electrolyte, in combination with a movable switch member drawing an arc in said chamber on the opening of the switch.

2. An electric switch comprising a liquid container, a readily vaporizing electrolyte of high heat absorbing capacity contained therein, an insulating member at least partially submerged in said electrolyte and having an interior chamber open to said electrolyte, in combination with a movable switch member drawing an arc in said chamber on the opening of the switch.

3. An electric switch comprising a liquid container, a readily vaporizing electrolyte of high heat absorbing capacity contained therein, a member at least partially submerged in said electrolyte and having an interior chamber open to said electrolyte, but vented to prevent excessive pressure therein, in combination with a movable switch member drawing an arc in said chamber on the opening of the switch.

4. An electric switch comprising a pair of switch terminals, and means for maintaining in the space between said terminals, in the open position of the switch, a circulating conductive and readily vaporizable liquid adapted to quench an arc formed between the terminals.

5. An electric switch comprising a pair of switch terminals, and means for maintaining in the space between the terminals, in the open position of the switch, a conductive

and readily vaporizable liquid rapidly circulated by the heat of an arc formed between said terminals.

6. An electric switch comprising a pair of switch terminals, and means for maintaining in the space between the terminals, in the open position of the switch, a conductive liquid rapidly vaporized and circulated by the heat of an arc formed between said terminals.

7. An electric switch comprising relatively movable contacts and an associated conductive and readily vaporizable electrolyte in which at least one of said contacts is immersed on the opening of the switch, together with means for insuring the rapid circulation of the electrolyte in the vicinity of the arc during the maintenance of the latter.

20 8. An electric switch comprising relatively movable contacts and an associated conductive and readily vaporizable electrolyte in which at least one of said contacts is immersed on the opening of the switch, said 25 electrolyte having the capacity to rapidly absorb the heat of the arc and thus to chill its path between the contacts, together with means for insuring the rapid circulation of the electrolyte in the vicinity of the arc during the maintenance of the latter.

30 9. The method of breaking an electric circuit which comprises separating a pair of contacts beneath the surface of a readily

vaporizing and heat absorbing electrolyte, trapping the vapor generated by the head 35 of the current flow in the electrolyte above the surface of the electrolyte, and causing the electrolyte to move downward and away from one of the contacts under the pressure 40 of said trapped vapor.

10. An electric switch comprising a liquid container, a readily vaporizing electrolyte of high heat absorbing capacity contained therein, an insulating member at least partially submerged in said electrolyte and affording a pressure chamber open at its lower portion to the electrolyte and substantially closed at its upper portion, in combination with a pair of cooperating relatively movable switch contacts, and means for separating said contacts to open the switch, one of said contacts in the open position of the switch being located in said chamber, whereby in the open position of the switch current is caused to flow through the electrolyte in said closed chamber and at least partially vaporize said electrolyte, the vapor so generated being trapped in the upper portion of the chamber and serving to depress the electrolyte and thus cause the same to 50 move away from the switch contact in said chamber.

In testimony whereof we have signed our names to this specification.

CHAS. G. ADSIT.
CHARLES E. BENNETT.
